INVENTOR:
20 Robert T. Smith,
BY: Chas. M. Gerard,
ATTORNEY.

UNITED STATES PATENT OFFICE

ROBERT T. SMITH, OF KANSAS CITY, MISSOURI

MULTIPLE-FUSE PLUG

Application filed August 19, 1929. Serial No. 386,924.

The present invention relates to fuse plug devices, and the primary object in view is to devise an improved multiple fuse construction for such plug appliances, adapted to render the appliance operative for a given number of times, depending upon the number of fuse elements embodied therein and adapted to be brought into operative position successively by the simple rotation of the movable part carrying the fuse elements, and thereby again restoring the electric circuit.

It is also sought to provide a neat, simple and compact, as well as sightly construction, adapted to be quickly operated, and also having means for visually indicating the number of fuse elements and the successive order in which they are brought into use.

With the foregoing general object in view, the invention will now be described by reference to the accompanying drawing illustrating one form of construction which I have devised for embodying the proposed improvements, after which those features and combinations deemed to be novel will be set forth and claimed.

In the drawing—

Figure 1 is a side view, illustrating a multiple fuse plug constructed in accordance with my invention;

Figure 2 is a central longitudinal sectional view;

Figure 3 is an enlarged sectional detail of the fuse-containing and adjusting parts of the device;

Figure 4 is an interior view of the parts shown in Figure 3; and

Figure 5 is a face view of the outer end of the plug.

Referring to the drawing in detail, this illustrates the improved device as comprising a hollow body or plug portion proper 8 adapted to be constructed of bakelite, porcelain or other suitable non-conducting material, having the exterior contact element 10 constituting one of the terminals of the plug, from which a pin or post 11 projects up centrally into the hollow interior chamber 12 of the plug. Surrounding the plug is the usual metallic shell 14 adapted to fit

the fuse plug-receiving socket and constituting the other terminal of the plug, and also having an extension projecting through the side wall of the plug and terminating in a lip or brush element 15 overhanging an interior annular shoulder 16 formed around the chamber 12 as illustrated in Figure 2.

The multiple fuse structure comprises a disk 18 of non-conducting material carrying the fuse elements which are formed with the central disk portion 19 having a plurality of radiating arms 20 (having the reduced neck portions 20') extending across one face of the disk 18, over its margin, and thence inwardly partly over the opposite face of said disk 18. An insulating washer 22 is fitted over the hub portion 21 of the disk 18 into retaining engagement with the terminations of the arms 20, as shown in Figure 3, while at the opposite face of the disk 18 the material thereof projects sufficiently past the exposed surfaces of said arms 20 to form ribs 24, and hence depressions between said ribs, for a purpose hereinafter explained.

The disks 18—19 are provided with a central opening 25 for mounting the same upon the inner end of an operating screw 26 having the external button 27, the enlarged shank portion 28 of said screw being journaled in an opening 29 in the cap piece or shell 30 fitting over the hollow end of the plug body 8 and having its side or cylindrical portion formed with detents 32 engaging corresponding recesses cut in the sides of said body, as illustrated in Figures 1 and 2.

A coil spring 35 is mounted around the screw 26 between the cap piece and the washer 22; a second insulating washer 36 is mounted on the screw between the spring and the cap piece, and both washers are formed with central bosses for centering the spring with reference to the screw.

Upon the inner end of the screw 26 is secured, by means of a nut 38, a spring jack element comprising the intermediate portion 39 engaging the screw and the spring arms 40 formed with the inturned overlapping and perforated terminals 41 for wip-

ing engagement with the post 11, as shown in Figure 2. The nut incidentally serves to secure the fuse disks upon the screw 26 with the hub portion 21 of the disk 18 in abutting engagement with the shank portion 28 of the screw, said shank portion preferably terminating in a squared formation for insuring positive turning movement of the disks in the operation of the device.

With the parts assembled as shown in Figure 2, the function of the spring 35 is such as to actuate the fuse member yieldingly in the direction of the shoulder 16, and, as the fuse structure is turned, by means of the button 27, bringing the arms 20 of the fuse elements successively opposite the contact lip or brush element 15, these arms are successively actuated into contact engagement with said lip 15. The depressions formed around these arms by the ribs 24 serve to latch the fuse structure in these successive positions, necessitating a slight retraction of the button and screw for unlatching the fuse member from engagement with the lip, preliminarily to each turning movement, as will be readily understood. The sliding contact between the arms 40 of the jack element and the pin 11 accommodates this retracting movement of the fuse structure.

Preferably, suitable vent openings 7 are provided in the sides of the plug for escape of gases from the interior whenever a fuse is blown.

It will thus be apparent that I have devised, a simple, practical and efficient multiple fuse plug structure adapted to fulfill the desired objects of the invention, and while I have illustrated the preferred form of construction, I desire to reserve the right to make such changes as may fairly fall within the scope of the following claims.

Having thus described my invention, what I claim and desire to secure by Letters Patent is:

1. A multiple fuse structure comprising a hollow plug element containing a pin terminal and an interior brush terminal, a cap piece fitting the open end of said plug, a rotary disk journaled in said cap piece and carrying a spring jack yoke slidingly engaging said pin terminal, a plurality of radial fuse elements carried by said disk for selective engagement with said brush element, said disk being formed with ribs separating said fuse arms and providing radial depressions between said ribs, and means permitting slight retracting movement of said disk for seating and unseating said brush element in said depressions.

2. A multiple fuse structure comprising a hollow plug element containing a pin terminal and an interior brush terminal, a cap piece fitting the open end of said plug, a rotary and axially movable pin carried by said cap piece, a disk carried by said pin and

provided with a plurality of radial fuse elements and ribs separating said elements and providing radial depressions between said ribs, a spring jack yoke slidingly engaging said pin terminal and provided with means securing the same on the inner end of said pin in engagement with the inner ends of said fuse elements, and means tending yieldingly to urge said pin and disk in the direction to maintain contacting engagement between said brush and fuse elements.

In witness whereof I hereunto affix my signature.

ROBERT T. SMITH.
